Patented Feb. 26, 1918.

Fig. 2.

UNITED STATES PATENT OFFICE.

SAMUEL B. CARR, OF HARRODSBURG, KENTUCKY, ASSIGNOR OF ONE-HALF TO R. L. BLACK, OF HARRODSBURG, KENTUCKY.

HEMP-BREAKING MACHINE.

1,257,313.

Specification of Letters Patent. Patented Feb. 26, 1918.

Application filed July 17, 1916. Serial No. 109,642.

To all whom it may concern:

Be it known that I, SAMUEL B. CARR, a citizen of the United States, residing at Harrodsburg, in the county of Mercer and State of Kentucky, have invented a new and useful Hemp-Breaking Machine, called the "Carr Automatic Hempbrake," of which the following is a specification.

The present invention appertains to hemp breaking machines, and aims to provide a novel mechanism for operating a machine of that character by an engine or prime mover in an effective manner.

It is also the object of the invention to provide a mechanism of the nature indicated which is comparatively simple and inexpensive in construction, as well as being efficient and practical.

The invention is illustrated in the accompanying drawing, wherein:—

Figure 1 is a plan view of the improved machine.

Fig. 2 is a side elevation thereof.

In carrying out the invention, there is provided a suitable frame 21, provided at one end with a shelf or auxiliary frame 22 connected thereto by braces 23 and adapted to support an engine or other prime mover for operating the machine. The frame is provided at its other end with a cross piece 9 to which the lower set of swords or blades 4 is attached, their free ends having attached thereto the bottom sword bar 1. The upper set of swords or blades 4 of the breaking device is fulcrumed or pivotally connected with the frame above the cross piece 9, and have attached to their free ends, the upper sword bar 2, springs or other buffers 3 being provided between the bars 1 and 2 for reducing the shock when the bar 2 is swung downwardly. Rigidly united with the upper set of swords 4 and disposed above the same, is a longitudinal bar 5, and an operating lever 6 is attached to a transverse rock shaft 10 mounted within the frame substantially in the same horizontal plane as the fulcrum of the upper set of swords 4 but spaced therefrom, whereby the lever 6 extends over the fulcrum of said swords. The free end of the lever 6 has the downwardly extending slotted member 7 slidably engaging the bar 5. A transverse crank shaft 15

is journaled to the upper portion of the frame above the intermediate portion of the lever 6, and its crank is connected by a link 55 or connecting rod 8 with the intermediate portion of said lever 6. A fly wheel 11 is preferably secured upon one end of the crank shaft 15 to provide for the uniform operation, and a pulley wheel 12 is connected 60 to the other end of the crank shaft and is connected by a belt 18 with a pulley wheel 13 mounted upon a counter shaft 16 carried by the frame above the rock shaft 10. The pulley wheel 13 is in turn connected by a belt 19 with the pulley wheel 14 upon a drive shaft 17 carried by the rear portion of the frame near the shelf 22, and said pulley wheel 14 can be connected by a belt 20 with an engine or other prime mover (not shown) 70 supported upon said shelf, whereby to transmit motion to the crank shaft 15. By the provision of the lever 6 having its free end slidably connected to the bar 5, and the link 8 connecting said lever 6 with the crank of the crank shaft, the rotation of the crank shaft will effectively oscillate the upper set of swords.

Having thus described the invention, what is claimed as new is:—

1. A hemp breaking machine embodying a frame, a set of swords fulcrumed thereto, a bar connected rigidly with said swords, a lever fulcrumed to the frame beyond the fulcrum of the swords and having its free end slidably engaging said bar, a crank shaft carried by the frame, and a link connecting the crank of said shaft and said lever.

2. A hemp breaking machine embodying a frame, a set of swords fulcrumed to one end of the frame, a bar connected rigidly with said swords and disposed longitudinally thereabove, a lever fulcrumed to the frame substantially in the same plane with the fulcrum of the swords and spaced therefrom, the free end of the lever having a slotted portion slidably engaging said bar, a crank shaft carried by the frame above said lever, and a link connecting the crank of said shaft and the intermediate portion of said lever.

SAMUEL B. CARR.
